UNITED STATES PATENT OFFICE.

CLIFFORD L. KEDDY, OF LYNN, MASSACHUSETTS.

TELEPHONE SYSTEM.

Application filed January 5, 1922. Serial No. 527,266.

To all whom it may concern:

Be it known that I, CLIFFORD L. KEDDY, a subject of the King of Great Britain, residing at Lynn, in the county of Essex and 5 State of Massachusetts, have invented certain new and useful Improvements in Telephone Systems, of which the following is a specification.

My invention relates to telephone systems 10 and it has for its object to improve the construction and mode of operation of the same.

Telephone systems have heretofore been so constructed that when the central operator 15 called a subscriber it was impossible, except when the subscriber answered the call of the central station, for the central operator to know whether or not the subscriber was absent from his station. When the central operator plugs in to call a subscriber, the supervisory lamp of the called subscriber at the central station is brightly lighted, and if the subscriber at the station being called answers the central operator's bell signal 20

25 and removes his receiver from the hook, the supervisory lamp of the called subscriber at the central station is dimmed, thus signaling the central operator that the called subscriber has responded to the bell signal.

30 This dimming of the calling lamp at the central station is occasioned by the removal from its hook of the receiver at the called subscriber's station, and said lamp at the central station remains dimmed so long as 35 the called subscriber maintains his receiver off the hook. When the called subscriber replaces his receiver upon the hook this supervisory lamp at central station is restored to its brightly lighted condition, thus

40 signaling the central operator that the call for which connections were established, is finished, whereupon the plug of the calling subscriber and the plug of the called subscriber are pulled from their jacks to re- 45 store the system to its normal condition.

In the event that the called subscriber is not present at his station when his call bell is operated and no one responds to the bell signal at that place, then it often happens 50 that the central operator continues to ring the called subscriber's bell for a long period of time, thus not only monopolizing a large part of the central operator's time in a fruitless effort to secure a response from 55 the called station, but also subjecting persons

in the vicinity of the called station to the annoyance of the continuously ringing bell at that station. Also, under such circumstances, the calling subscriber has monopolized the use of a line to the exclusion of 60 others for an objectionally long period of time, without results or profit to the telephone company. My invention aims to obviate this objectionable feature of telephone systems as heretofore constructed, and 65 it consists in providing a system of this kind with means at the called subscriber's station, that is manually set or adjusted by the subscriber at that station when departing from his office or other place where his 70 telephone instrument is located, whereby when the central operator calls that station by operating the bell circuit as described, a signal is automatically operated or produced at the central station which informs 75 the central operator that the subscriber is absent.

Other features of my invention are herein-after pointed out.

In the accompanying drawings:

Figure 1 is a diagrammatic view of a telephone system constructed in accordance with my invention, and comprising two subscribers' stations and a central station.

Figure 2 is an enlarged diagrammatic view of one of the subscribers' stations.

In Figure 1 of the drawings, A and B are two subscribers' stations, and O the central station. Central station O is constructed as usual, and is connected with the subscribers' 90 stations A and B by two pairs of line wires a, a', and b, b'.

At each subscriber's station (see Fig. 2), the line wire a is connected with one end of the winding of the primary p of the induction coil I, the other end of said winding being connected by a wire a⁷ with a stationary contact a⁸ co-operating with the hook H. The hook H is connected by a wire a⁹ with one binding post of the transmitter 95 T, whose other binding post has connected to it the other line wire a'. One end of the secondary of induction coil I is connected by a wire a¹⁰ and the wire a⁷ with the contact a⁸, while the other end of said winding is connected by a wire a¹¹ with one of the binding posts of receiver R. The other binding post of receiver R is connected by wire a¹² with one side of the condenser C, the other side of said condenser being con- 110

nected by a wire a^{13} with the line wire a' . The usual bell magnet a^{14} has one end of its winding connected with wire a^{12} by a wire a^{15} , while the other end of its winding is connected by a wire a^{16} with a stationary contact a^{17} . This stationary contact is cooperatively disposed with relation to a movable contact a^{18} connected by a wire a^{19} with line wire a . Thus, so far as described, the construction at each subscriber's station is, with the exception of the switch a^{17} , a^{18} , in all respects the same as heretofore.

At the central station one of the multiple jacks connected to A's line is shown at a^5 , and the answering jack and line lamp at a^6 and a^3 respectively. One of the multiple jacks of B's line is shown at b^5 and the answering jack and line lamp at b^6 and b^3 respectively. In the event that the subscriber, 20 A, for example, desires to call, he removes his receiver R from its hook H, thereby lighting the line lamp a^3 , and the central operator sitting before the answering jack, plugs into the answering jack with the result that current is sent through the shank wire of the plug to the ring o^2 of the jack and thence through the cut-off relay o^3 to ground, thereby cutting off direct battery from the line at o^3 and putting out the line 30 lamp a^3 . The circuit closed by the removal of the receiver R from its hook H at station A is traced as follows: from ground at G, through wire o^4 , line battery X', wire o^5 , relay o^6 , wire o^7 , (relay o^3 being normally 35 de-energized), wires o^8 and o^9 to line wire a of station A, primary p , wire a^7 , contact a^8 , hook H, wire a^9 , transmitter T, line wire a' of station A, wires o^{10} and o^{11} , switch o^{12} and wires o^{13} and o^{14} to ground. The closing 40 of this circuit through relay o^6 results in the closing of switch o^{15} , which is in the circuit of line lamp a^3 . This circuit of line lamp a^3 is traced as follows: from ground G' through wire o^{16} , battery o^{17} , wire o^{18} , lamp a^3 , wires o^{19} and o^{20} , switch o^{15} and wires o^{21} and o^{13} to ground again. The receiver R being off the hook H at A when the central operator plugs into jack a^6 , current flows out on the line through the windings 1 50 and 2 of the repeating coil, and thus the supervisory relay o is energized and the shunt circuit thereof being closed the supervisory lamp p does not glow. The circuit of supervisory relay o which is thus 55 completed at jack a^6 is traced as follows: from one side of battery X through wire o^{22} , coil 1, the winding of relay o , wire o^{23} , key K, wire o^{24} , wire o^{25} , wire o^8 , line wire a of station A, primary p , wire a^7 , contact a^8 , hook H, wire a^9 , transmitter T, line wire a' of station A, wires o^{10} and o^{26} , cord wire o^{27} , switch K, wire o^{28} , coil 2, and thence 60 through wire o^{29} to the opposite side of battery X. At this stage the calling subscriber's transmitter is fed by current sent out 65

through the repeating coil, direct battery is cut off the line, the circuit of line lamp a^3 is open and the supervisory lamp p shunted out.

When the operator at central inserts the 70 calling plug into the jack b^5 of the called subscriber, B, for example, the cut-off relay o^{30} is energized and direct battery cut off the line at switch o^{36} thereof. The receiver at B being on the hook, the line is open both 75 at the hook and at the condenser, so that no current flows through the supervisory relay o' , and therefore the shunt around the lamp p' is open and the lamp illuminated when 80 the central operator first plugs into jack b^5 , said circuit being indicated by the arrows in Figure 1. Directly B removes the receiver from the hook to answer, the line is closed through the primary coil, hook and transmitter, and current flows from the battery X 85 through the windings 3 and 4 of the repeating coil to the called telephone at B, and the relay o' is energized, with the result that the shunt around lamp p' is closed and p' is dimmed, and this is the state of things during 90 conversation. The circuit closed through relay o' through the removal of the receiver from the hook at the called station, and which results in the dimming of the supervisory lamp p' when the called subscriber 95 responds to the operation of his bell signal, is traced as follows: from one side of battery X, through wire o^{22} , coil 3, wire o^{37} , the winding of relay o' , wire o^{38} , key K', cord wire o^{39} , wire o^{40} , line wire a' of station B, primary p at B, wire a^7 at B, contact a^8 at 100 B, hook H at B, wire a^9 at B, transmitter T, and thence through line wire a of station B, wire o^{41} , cord wire o^{42} , switch K', wire o^{43} , coil 4, and wire o^{29} back to the opposite side 105 of battery X. This circuit through relay o' , however, is only completed in the event that the called subscriber removes his receiver from its hook, and heretofore the only signal transmitted to the central operator through this circuit has been the dimming of the supervisory lamp p to inform the central operator that the called subscriber 110 has responded to her signal by removing the receiver from the hook. It is to be observed and remembered that the circuit through the relay o or o' is broken at the switch K' each time the central operator moves said switch from its normal position to ring the bell at 115 the called subscriber's station. It is also to be noted that the supervisory lamp p or p' of the called subscriber has heretofore remained continuously brightly lighted until the called subscriber removed his receiver from the hook, the dimming of said supervisory lamp occasioned by the removal of the receiver from the hook being the signal to the central operator that the called subscriber 120 has responded, and, as pointed out, 125 this dimming of the supervisory lamp has

heretofore been the only signal returned from the called station in response to the operation of the bell at that station.

In carrying out my invention I provide at 5 each subscriber's station a movable switch member a^{18} , (referred to above), connected by a wire a^{19} with one of the line wires of that station and two stationary contacts a^{17} , (referred to above), and a^{20} . It will be 10 clear that when the movable contact a^{18} is in engagement with the stationary contact a^{17} the operation of the apparatus at the subscriber's station is substantially the same as heretofore, the signal bell a^{14} and condenser C being disposed in a shunt connecting the two wires as usual, so that when the central operator depresses key K' after plugging into the calling jack b^5 , the usual bell a^{14} will be sounded so long as contacts 15 a^{17} and a^{18} are in engagement. The contact a^{18} is accessible to the subscriber and is adapted to be manually adjusted by him so as to be engaged either with the contact a^{17} or with the contact a^{20} .

20 The contact a^{20} is connected by a wire a^{21} with one end of the winding of a magnet a^{22} , the opposite end of said winding being connected by a wire a^{23} with that portion of the bell shunt that is between the bell a^{14} and condenser C. The armature a^{24} of magnet a^{22} carries a striker a^{25} co-operating with two bells a^{26} . A spring a^{27} connected with an arm a^{28} projecting from armature a^{24} holds said arm against a stop 25 a^{29} with armature a^{24} at the limit of its movement away from the magnet. Resting upon arm a^{28} is a rod a^{30} freely movable vertically within a stationary guide a^{31} , and at its upper end said rod carries a piston 30 a^{35} loosely mounted within a stationarily supported cylinder a^{32} normally closed at its upper end by a valve a^{33} . This valve is hinged at a^{36} to the cylinder and near its middle is formed with a small vent hole a^{34} .

35 The rod a^{30} has fixed to it a laterally extending contact arm a^{37} co-operating with, but normally occupying a position below, and out of engagement with, a stationary contact a^{38} connected by a wire a^{39} with one line 40 wire a . As herein shown this wire a^{39} is joined to the wire a^{10} so that contact a^{38} is connected with line a through the primary p of induction coil I. The metal guide a^{31} is connected by a wire a^{40} with hook H, and through wire a^9 and transmitter T with line a' .

45 It will be understood that the outer pair of contacts of each key K and K' is connected, as usual, by wires, not shown, with a generator. Also, that when the central operator depresses either key K or K' the pair of middle movable contacts is shifted from the inner pair of contacts to the outer pair of contacts, thereby throwing the generator current onto the line to ring the bell 50

55 a^{14} at the subscriber's station. When switch a^{18} is on contact a^{17} and the generator current is thus thrown onto the line the usual signal bell a^{14} is sounded, and this will be the condition of things while the subscriber 55 is present at his station. When, however, the subscriber is about to leave his station and desires to have the central operator informed of the fact that he is absent should he be called during his absence, then the subscriber shifts the switch member a^{18} over onto contact a^{20} and leaves it there until his return. Should a call be made for his station during his absence, the bell ringing generator current passes from line a through 60 wire a^{19} ; switch member a^{18} ; contact a^{20} ; wire a^{21} ; bell magnet a^{22} ; wires a^{23} and a^{15} ; condenser C and wire a^{13} to the other line wire a' . This causes magnet a^{22} to attract its armature whose arm a^{28} shoves the rod a^{30} upward carrying contact a^{37} against contact a^{38} , and whose striker a^{25} sounds the lowermost bell a^{26} . This engagement of contacts a^{37} and a^{38} closes the shunt $a^{39}-a^{40}$ 65 around bell magnet a^{22} for the generator current, thus cutting out the bell magnet a^{22} whose armature is restored to its normal position by spring a^{27} , thus causing the striker to sound upper bell a^{26} . Rod a^{30} , contact a^{37} and piston a^{35} then fall by 70 gravity to their normal positions again, but slowly owing to the restricted air inlet a^{34} . The engagement of contacts a^{37} and a^{38} has the same effect upon the supervisory relay o or o' as is produced when the receiver R is removed from the hook. That is, assuming that station A is being called by central, the depression of key K' brings contacts a^{37} and a^{38} into engagement so that when key K' is restored to normal position, relay o' is energized and closes the shunt o^{45} , o^{46} and o^{47} at central, thereby 75 dimming supervisory lamp p' . In other words, the supervisory lamp p' shows bright 80 when central plugs into A's calling jack b^5 , but is momentarily dimmed each time key K' is restored after ringing A's bell, and this informs the central operator that the subscriber at A is absent. As pointed out 85 above, the circuit of relay o' is opened at key K' each time the operator depresses said key, so that while said circuit is thus open lamp p' glows brightly, but each time key K' is restored the circuit through relay o' is closed at the key (as well as at 90 a^{37} and a^{38}) and lamp p' shows dim and remains so until contact a^{37} moves down out of engagement with contact a^{38} . Thus, during ringing operations made to call the 95 absent subscriber, the lamp p' alternately shows bright and dim, whereas under normal conditions, (that is, with contact a^{17} on contact a^{17}) the lamp p' remains continuously bright during ringing operations 100

105 During the upward movement of rod a^{30} 105

110

115

120

125

130

under the influence of the armature arm a^{28} the piston a^{25} moves freely and unretardedly within the cylinder a^{32} , the valve a^{33} being free to open outwardly. At the conclusion of the upward movement of piston a^{25} , however, the valve a^{33} closes, so that the descent of rod a^{30} and parts carried thereby, including the contact arm a^{37} , is checked or retarded, so that said parts move downwardly under the influence of gravity slowly, owing to the restricted vent port a^{34} . This insures the lamp p' being maintained dim for an appreciable period of time after key K' has been restored to its normal position.

15 It is intended that the subscriber upon returning to his station shall shift the contact a^{18} back onto the contact a^{17} , but should he forget or neglect to do this, the sounding of the bells a^{26} upon the occasion of the first 20 call after his return will remind him to do so.

It will be clear to those skilled in this art that the only change necessary to be made in the system as heretofore constructed is 25 the provision of the switch $a^{17}-a^{18}$ in the conductor $a^{16}-a^{19}$, the joining of conductor a^{23} with conductor a^{15} and the provision of a small number of additional parts at the subscriber's station including magnet a^{22} and 30 parts that are associated therewith, and that these parts may be made up or constructed as an attachment, including the switch $a^{17}-a^{18}$, that is comparatively inexpensive and easily applied to the subscriber's instrument.

35 What I claim is:

1. A telephone system having in combination a plurality of stations; signal instruments at said stations; signal circuits connecting said stations; means through which a person at one station operates the signal circuit of the other station to call the latter, and means under the control of the person at the called station adapted to be 40 manually adjusted so as to automatically produce a visual "absent" signal at the calling station when the signal circuit of said called station is operated.

2. A telephone system having in combination a plurality of stations; signal instruments at said stations; signal circuits connecting said stations; means through which a person at one station operates the signal circuit of the other station to call the latter, and means under the control of the person at the called station adapted to be 45 manually adjusted so as to automatically operate the signal circuit of the calling station to pro-

duce a visual absent signal at said calling station when the signal circuit of said called station is operated.

3. A telephone system having in combination two stations; two signal instruments, one at each station; two signal circuits connecting said stations, one for each signal; means through which a person at one station operates the signal circuit of the other station to call the latter, and means under the control of the person at the called station adapted to be manually adjusted so as to automatically operate the signal circuit of the calling station to produce a visual absent signal at said calling station when the signal circuit of said called station is operated.

4. In a telephone system the combination with the two line wires at a subscriber's station, of a normally closed main shunt circuit connected with said line wires; a bell in said main shunt circuit; a condenser in said main shunt circuit; a second shunt circuit around said bell having one end thereof connected with said main shunt circuit between said bell and said condenser; a relay in said second shunt; a normally open switch operated by said relay; a third shunt connected at its ends with said line wires and in which said normally open switch is arranged; and shunt controlling means adapted to be adjusted by the operator at the subscriber's station to either open said main bell shunt circuit and close said second shunt circuit, or to open said second shunt circuit and close said main bell shunt circuit.

5. In a telephone system the combination with a plurality of subscribers' stations each equipped with telephone apparatus including a transmitter, receiver, hook and bell; a central station equipped with central station apparatus including jacks, plugs, ringing keys, supervisory relays; supervisory lamps and circuits for said instrumentalities, and line wires connecting the subscribers' stations with the central station, of means at each subscriber's station that is normally inoperative but adapted to be set or adjusted by the subscriber so as to be operated by the ringing current to automatically control the supervisory lamp of that station at the central station to produce a visual signal indicating to the central station operator that the subscriber is absent from his station.

In testimony whereof I have affixed my signature.

CLIFFORD L. KEDDY.
